Douglas W. Schelling(57) **CLAIM**

What is claimed is the ornamental design for bulged eye goggles, as shown and described.

DESCRIPTION

FIG. 1 is a front elevation of the bulged eye goggles of applicant's invention.

FIG. 2 is a top elevation and a bottom elevation of the bulged eye goggles of applicant's invention, both sides being identical.

FIG. 3 is a back elevation of the bulged eye goggles of applicant's invention.

FIG. 4 is a left elevation and a right elevation of the bulged eye goggles of applicant's invention, both sides being identical; and,

FIG. 5 is a top elevation of the bulged eye goggles of applicant's invention showing the flexibility of the design. The broken lines shown in FIGS. 1-5 are for illustrative purposes only and form no part of the claimed design.
